UNITED STATES PATENT OFFICE.

WILLIAM F. PAGEL, OF Sycamore, Illinois.

TORCH FOR PLUMBERS' USE.

Application filed April 17, 1922. Serial No. 554,246.

To all whom it may concern:

Be it known that I, WILLIAM F. PAGEL, a citizen of the United States, and resident of Sycamore, in the county of De Kalb and State of Illinois, have invented certain new and useful Improvements in a Torch for Plumbers' Use, of which the following is a specification.

My invention relates to improvements in 10 torches of the type known as plumbers' torches, the object of my invention being to simplify and improve the construction of the torch and particularly of the fuel feed and air control devices.

15 A further object is to provide means whereby the entrance end of the fuel delivery tube within the tank will always be immersed in the fuel regardless of the position in which the torch is placed in while 20 being used, so long as there is sufficient fuel in the tank.

My invention resides in a plumber's torch having a closed tank for containing the fuel, which tank is free of openings except one filling opening at the top and which filling opening is adapted to be closed by the feed devices for the burner. Furthermore the burner, feed devices, and pump are arranged in a unitary structure 10 so that the torch as a whole consists only of this unitary structure and the tank.

A further feature of my invention is found in a flexible fuel delivery pipe which depends within the tank and which is adapted to fall to such a position relative to the position of the tank that its inlet end is always immersed in the liquid fuel in the tank so long as there is sufficient fuel to reach the lower end of the pipe. In other words, if the tank is tipped out of its normal position, the feed tube being flexible, its lower inlet end hangs downwardly and is immersed in the fuel.

A further feature of importance relates to a simple safety valve connected with the air passage which is adapted to prevent an excessive pressure being applied to the tank and in combination with this safety valve, I arrange a manually operable relief valve which is adapted to release all pressure from the tank at times when the torch is not in use.

A particular object of my invention is to provide a plumber's blow torch so constructed that the fire hazard incident to the use of such torches is eliminated.

My invention will be more readily understood by reference to the accompanying drawings forming part of this specification, and in which:

Figure 1 is a fragmentary vertical central sectional view of the torch, parts thereof being shown in side elevation;

Figure 2 is a fragmentary vertical transverse sectional view on the line 2-2 of Figure 1;

Figure 3 is a detail sectional view of the inlet end of the flexible feed tube;

Figure 4 is a fragmentary view similar to Figure 1 showing a slight modification of my invention;

Figure 5 is a horizontal sectional view on the line 5-5 of Figure 4;

Figure 6 is a fragmentary sectional view on the line 6-6 of Figure 5, and

Figure 7 is a horizontal sectional view on the line 7-7 of Figure 1.

In said drawings, 1 represents the tank of the torch which is made up of an outer or main sheet metal member 2 in the form of an inverted deep cup and a sheet metal bottom 3 which is curved upwardly within the lower end of the main member 2 so that it will withstand the pressure which is used in such torches, the lower ends of these two members being rolled together and soldered, as shown at 4, providing a closed sheet metal tank.

The tank has a central opening 5 in its flat upper wall 6. This opening receives a nozzle 7 depending from a cup member 8, the nozzle being externally threaded to receive a locking nut 9 within the tank for securing the cup in position. This locking nut is adapted to be soldered to the shell 95 to prevent possible leakage at this point. The cup 8 is provided with an external upwardly extending circumferential flange 10 to assist in filling the tank with liquid fuel. The nozzle 7 has a central bore 11 forming a filling opening and which is internally threaded to receive a threaded stem 12 on a head member 13. This member is provided with a flange 14 which carries a suitable packing washer 15 adapted to contact with a concentric rib 16 on the cup so that when the head 13 is secured with the stem 12 in the threaded opening 11, the packing washer 15 and concentric rib 16 effect the hermetical sealing of the tank at this point.

The member 13 extends horizontally, one end being provided with an internally threaded nozzle

17 for receiving a pump cylinder 18 and the opposite end having an integral elbow 19 formed to receive a connecting pipe 20 upon the upper end of which is arranged 5 the burner 21 of the torch. Below the pump cylinder 18 which extends horizontally, the member 13 is provided with a horizontal arm 22 which extends out beyond the tank 1 and is provided with a depending hand 10 grip or handle 23. Upon the upper end of the handle, I provide an integral ring 24 through which the barrel of the pump extends and by which the pump is steadied.

The pump is provided with a piston 25 of 15 suitable character operable by means of a handle 26 secured on the outer end of a piston rod 27. The member 13 is provided with a central vertical passage 28 which extends down through the stem 12 for delivering air from the pump to the tank and at the upper end of this passage the member is provided with a valve chamber 29 within which is arranged a spring-pressed 20 check valve 30 and a small passage 31 leads 25 from the pump cylinder to the valve chamber, said passage 31 being closed by the valve 30. The valve chamber 29 is closed at its outer end by a screw plug 32 and I provide a suitable spring 33 for holding the 30 valve to its seat and preventing the escape 35 of air from the tank back to the pump. The member 13 is also provided with a fuel feed delivery passage 34 which extends outwardly to the elbow 19 for delivering fuel 40 to the burner and also extends downwardly through the stem 12. For the purpose of 45 feeding the fuel from the lower part of the tank to said feed passage, I provide a flexible delivery tube 35 having a threaded 50 connection 36 at its upper end adapted to be screwed into an enlarged opening 37 at the lower end of the feed passage 34. Upon the lower end of the delivery pipe 35 I secure a head 38. This head is in the form of a cap 45 having a central inlet opening 39 in its lower wall 40. The lower wall 40 is spaced from the extreme lower end of the tube and in this space I provide a fine wire screen 41 for preventing any dirt or dust entering 55 the tube 35. The cap 38 not only provides means for holding the screen 41 in position but also provides a weight for the lower end of the feed tube which causes the lower end of the feed tube to fall by gravity if 60 the torch is tipped, and in thus falling, the lower end is carried into the liquid, as indicated in dotted lines in Figure 1 wherein the dotted line 42 represents the level of the liquid when the torch is tipped.

60 In filling the torch the member 13 with all of its attached parts is unscrewed and removed and then the liquid can be poured into the cup 8 and flows through the threaded opening 11 into the tank.

65 I provide means for automatically relieving

the reservoir of excessive pressure so as to prevent a possible rupture of the reservoir when applying pressure by means of the air pump. This relief means consists of a spring pressed safety valve 43 closing one 70 end of a transverse passage 44 connected with the passage 28 through which air is delivered to the reservoir. This valve is mounted in a valve chamber 45 on the member 13 and which is closed at its outer end 75 by a screw plug 46. The chamber 45 is provided with a suitable vent opening 47.

The opposite end of the transverse passage 44 is closed by a needle valve 48 which is 80 manually adjustable to close or open the passage 44, and having a suitable vent opening 49 provided to permit the free relief of the tank when the valve 48 is unseated. The safety valve 43 automatically relieves 85 the reservoir of excessive pressure and the valve 48 is used to relieve the reservoir of all pressure when the torch is not in use.

It is to be noted that there is but one opening into the tank which has to be sealed in contradistinction to the many openings in 90 torches as heretofore made. Further it is to be noted that all the machine work and assembling is confined to a unitary structure including the burner, the delivery tube, the pump, the handle, and the various valves 95 thus greatly simplifying the manufacturing operations and reducing the cost of such devices.

The above advantages are also found in the form of my invention illustrated in Figures 4 to 6 inclusive.

In this modified form of my invention I have shown the same form of unitary burner and handle member with some distinctions 105 of importance.

The most noticeable of these is the vertical arrangement of the air pump 50 instead of the horizontal arrangement shown in Figure 1. I provide the head member 51 which is similar to the member 13 in Figure 1, with a depending hollow handle part 52 closed at its lower end and in which I mount the pump 50. The upper end of the barrel of the pump is provided with an externally threaded head or collar 53 adapted to be received in and to close the upper end of the hollow handle. The pump cylinder does not fill the hollow handle and from the upper part of the hollow handle an air delivery passage 54 leads through the member 51 and through the mounting nozzle 7 into the reservoir as in the former instance. As in the form shown in Figure 1, I provide a flexible tube 35 through which the liquid fuel is delivered to the burner through the 115 delivery passage 34.

I provide means for regulating the flow of the fuel through the fuel delivery passage 34 which operates to cut the flow down to an amount just sufficient to keep the burner hot 120

at times when the maximum flame is not required.

This means consists of a needle valve 55 adjustably mounted in the member 51. This valve enters the passage 34 and is adapted to close off same more or less in an obvious manner. The valve 55 is ordinarily set to allow just sufficient flow of fuel through the passage 34 to keep the burner hot and I provide means so that the operator can conveniently and readily open the valve to allow a sufficient flow of fuel to maintain the maximum flame. This means consists of a lever handle 56 fixed on the stem of the valve 55 by a set screw 57. The lever 56 projects along side of the member 51 toward the handle 52 and has a thumb piece 58 conveniently located to receive the thumb of the operator when grasping the handle 52 with the right hand.

By swinging the lever 56 toward the member 51 the valve is opened and I provide a spring 59 arranged between the lever 56 and the member 51 to normally maintain the valve 55 at the minimum flow position. The spring 59 is held on a stem 60 which is rigid with the lever 56 which stem projects through an opening 61 in the member 51.

Sometimes it is desired to arrange the valve 55 to remain at its maximum flow position and I accomplish this and relieve the operator of continuously holding the valve open by providing a projection 62 in the opening 61 adapted to be received in a notch 63 in the stem 60 when the stem is pushed through the opening 61 far enough.

The swinging of the lever 56 will cause the projection 62 to engage in the notch 63 the parts being yielding enough to permit this engagement and when it is desired to release the stem and permit the valve 55 to close to its minimum flow position, it is merely necessary to force the free end of the stem away from this projection by a slight pressure on the stem.

To provide a fine adjustment of the valve 55 for normal low or minimum fuel feed, I provide an adjustable nut 64 on the free end 65 of the stem 60 and adapted to contact with the side of the member 51 to limit the throw of the lever 56 by the spring 59. By adjusting the nut 64 in or out as the case may be, the valve 55 is obviously adjusted for more or less minimum feed as may be necessary.

The modified form of my invention is also provided with the transverse passage 44 controlled by a safety valve and a manually operable relief valve as in the form first described.

While the connection of the unitary structure, comprising the pump, handle, burner, and the several connections, devices and valves, with the reservoir, as described, is rigid and strong enough for all ordinary

usage, I have found that it is advantageous to brace this unitary structure to prevent any straining of the connection with the reservoir. This is particularly advisable as a precaution against possible accident and fire should the torch accidentally fall and strike on an extending part of the unitary structure. Such an accident might possibly cause a leak at the single opening which I provide into the reservoir. For the purpose of making doubly sure that such a leak will not occur I brace the lower end 66 of the depending handle, either in the solid form shown in Figure 1, or the hollow form shown in Figure 1', rigidly to the reservoir. This bracing means consists of a brace projection 67, preferably integral with the lower end 66 of the handle, extending inwardly from its inner side or edge toward the reservoir, its end being provided with thin lateral projections 68 curved around the reservoir. I provide a flat sheet metal band or ring 69 extending entirely around the reservoir in the form of a hoop, the ends 70 of the ring being secured to the two projections 68 at the inner end of the brace 67 by rivets 71. The hoop or ring 69 fits on the outer cylindrical surface of the reservoir and can be rotated thereon as the head 13 or 51 is mounted on the reservoir by screwing the nozzle 7 into the threaded opening 11.

It will be obvious that when the nozzle 7 of the unitary structure is screwed into the reservoir the unitary structure is rigidly braced and cannot accidentally strain the connection of these two members even should the torch fall and strike upon a projecting part of the unitary structure.

As many modifications of my invention will readily suggest themselves to one skilled in the art, I do not limit or confine my invention to the specific details of construction herein shown and described.

I claim:

1. The improvements herein described comprising a plumber's torch having a closed sheet metal tank provided with but one opening, said opening being arranged at the top of the tank, and a unitary structure comprising an air pump, a burner and connections adapted to be secured in said opening, said structure having a horizontally extending, rigid, integral bracket arm for supporting the pump.

2. In a plumber's torch having a closed tank provided with a filling opening at its top, a unitary structure including a threaded stem for closing said opening, an air pump carried by said stem and passages provided in the stem for delivering air from the pump into the tank, a relief passage in said structure between the pump and the tank and connecting with the open air, and a spring pressed relief valve controlling said relief passage.

3. In a plumber's torch having a closed tank provided with a filling opening at its top, a threaded stem for closing said opening, an air pump carried by said stem and 5 passages provided therein for delivering air from the pump into the tank, and a manually operable relief valve arranged between the pump and the tank as and for the purpose specified.
- 10 4. In a device of the kind described, a unitary structure carrying an air pump and a burner and having a screw threaded stem for mounting it upon a fuel tank, the structure having a threaded socket for receiving 15 the pump barrel, and provided with a ring support for engagement with the barrel of the pump between its ends, as and for the purpose specified.
- 15 5. The improvements herein described comprising a plumber's torch having a closed sheet metal tank provided with but one opening, said opening being arranged at the top of the tank, and a unitary structure comprising an air pump, a handle, and connections adapted to be secured in said opening, 20 said structure having a horizontally extending, rigid, integral bracket arm for supporting the pump.
- 25 6. The improvements herein described comprising a plumber's torch having a closed sheet metal tank provided with but one opening, said opening being arranged at the top of the tank, and a unitary structure comprising an air pump, a handle, the necessary 30 control valves and a feed pipe adapted to depend within the reservoir of the torch, and means for rigidly bracing the unitary structure to the reservoir while permitting 35 the rotation thereof for mounting and de- 40 mounting it.
7. The improvements herein described comprising a plumber's torch having a closed sheet metal tank provided with but one opening, said opening being arranged at the top of the tank, and a unitary structure 45 comprising an air pump, a handle adapted to depend alongside the reservoir, and means for bracing the lower end of the handle relatively to the reservoir, such bracing permitting the free rotation of the unitary 50 structure for mounting and demounting.
8. The improvements herein described comprising a plumber's torch having a closed sheet metal tank provided with but one opening, said opening being arranged at the 55 top of the tank, and a unitary structure comprising an air pump, a handle adapted to depend alongside the reservoir, the lower end of the handle having a rigid projection extending toward the reservoir and a 60 ring fitting upon the reservoir and rigidly secured to said projection for bracing the unitary structure and permitting its free rotation, as and for the purpose specified.
9. In a torch of the kind described, a tank having a filling opening in its top, a plug for said opening, an air pump arranged horizontally and supported upon said plug, 65 said plug forming part of a unitary structure which carries the burner for the torch, 70 and a fuel delivery pipe secured to the inner end of the plug and adapted to depend in the tank, an air pump barrel screwed into a threaded opening in said plug, and a horizontal extending bracket provided with 75 a ring for surrounding the pump barrel and retaining it in position.

Signed at Chicago, Ill., this 14th day of April, 1922.

WILLIAM F. PAGEL.
